UNITED STATES PATENT OFFICE.

WILLIAM VITZTHUM, OF HOBOKEN, NEW JERSEY, ASSIGNOR TO MAX KATZENBERG, G. GARSON FREUND, AND MAX FREUND, OF NEW YORK, N. Y.

DESIGN FOR A BELT.

SPECIFICATION forming part of Design No. 38,402, dated October 16, 1900.

Application filed September 13, 1900. Serial No. 29,969. Term of patent 3½ years.

To all whom it may concern:

Be it known that I, WILLIAM VITZTHUM, a citizen of the United States, residing at Hoboken, county of Hudson, State of New Jersey, have invented and produced a new and original Design for a Belt, of which the following is a specification.

My invention relates to belts, and the essential feature of said invention resides in the shape and configuration of the article herein shown and described.

In the drawings forming part of this specification, Figure 1 is a front elevation of the belt as it appears when in use, and Fig. 2 is a side elevation of the complete belt opened out.

In side elevation the belt appears as a flattened double yoke and comprises, as to configuration, substantially three parts, to wit: the part 1, curved downwardly, and the parts 2 3, of a reverse curve and curved upwardly, their ends 4 5 having a downward curve.

The curve 6 of the upper edge of the belt

is of less depth than the curve 7 of the lower edge of the belt, as illustrated. 25

The ends 2 3 gradually taper to a point from the central section 1. The taper of the ends of the belt and their upward curve when in use are illustrated in Fig. 1, the ends overlapping from their point of securement to each other and which curve downwardly in reverse directions. Intermediate of the limits of the end sections 2 3 is secured a two-part fastener 8 9, the part 8 of which is exteriorly presented at the crossing of the end pieces when the belt is disposed as in Fig. 1. 30

Having described my invention, I claim—

The design for a belt substantially as herein shown and described.

Signed at the city, county, and State of New York this 7th day of September, 1900. 40

WILLIAM VITZTHUM.
